UNITED STATES PATENT OFFICE.

LEONARD A. SMALLWOOD, OF BIRMINGHAM, ENGLAND; ALFRED SMALLWOOD
ADMINISTRATOR OF SAID LEONARD A. SMALLWOOD, DECEASED.

METALLURGICAL FURNACE.

1,082,828.

Specification of Letters Patent. Patented Dec. 30, 1913.

Application filed June 18, 1910. Serial No. 567,639.

To all whom it may concern:

Be it known that I, LEONARD ALFRED SMALLWOOD, a subject of the Kingdom of Great Britain, residing at Tamworth House, 5 Livingstone Road, Handsworth, Birmingham, in the county of Warwick, England, tube manufacturer, have invented certain new and useful Improvements in Metallurgical Furnaces, of which the following is a 10 specification.

This invention comprises an improved furnace which may be advantageously adapted for the re-heating of metals, as for instance the heating of billets, projectiles, 15 large forgings and the like, and which, in certain cases, is also adapted for the roasting, calcining and smelting of ores. According to the present invention, I combine a single grate or other source of heat with 20 dual combustion chambers in a more efficient manner, the fuel-economy of a single grate or the like being coupled with the regenerative principle of reversing or alternately directing the flow of gases through 25 the two combustion chambers, and I am thus enabled to obtain a degree of economy with the improved furnace which is unattainable with either of said factors *per se*.

In carrying the invention into effect, the 30 material treated is preliminarily heated by the waste gases of the furnace or by radiation, after which they are introduced into a primary chamber in which a particularly high intensity of heat is maintained. While 35 it has been said that the preliminary heating is effected by the "waste" gases it will be readily understood that the said gases, issuing as they do from the primary chamber, contain an exceptionally large quantity 40 of heat with the result that the preliminary heating may be carried on until the temperature of the material treated is only a few hundred degrees short of that in the primary chamber. Since also the furnace products 45 are first brought into contact with the material treated which are already at a high temperature, the process of combustion is accelerated rather than impeded, inasmuch as the billets, within the primary chamber 50 being at an incandescent heat effectively consume the smoke and uncombusted products, so that when the furnace gases reach the preliminary heating chambers and cold material to be treated contained therein, 55 they are so completely combusted that the

working of the furnace is not appreciably affected by the relatively cold materials with which the gases then come into contact, the heat being readily diffused into contents of the chamber without the formation of 60 smoke as is the case where the furnace products are brought direct from the fire-grate into contact with the freshly introduced material.

The roasting, calcining or preliminary 65 heating of ore is effected in the chamber which the furnace gases enter after passing through the smelting chamber and when smelting in the one chamber is complete the fire box is placed in communication with the 70 other chamber containing the preliminary heated material and during the smelting of such material the contents of the finished chamber are removed and replaced by fresh ore requiring preliminary heating. The gases 75 issuing from the smelting chamber being at a very high temperature the unsmelted ore is heated in a material degree,—to within a few hundred degrees of fusing point, and on the dampers being reversed and the full heat 80 of the fire box directed to the ore at this temperature, fusion readily sets in and the process of combustion is in no way impeded as would be the case if cold or practically 85 cold matter were placed upon the smelting hearth. It will thus be understood that the furnace is continuous, that is to say, while one quantity of material is being smelted a subsequent quantity is being preliminarily 90 heated so that upon the operation of smelting being complete, the ore to be smelted has already been preliminarily heated.

In the drawing, forming part of this specification: Figure 1 is a sectional elevation of a furnace constructed in accordance 95 with the present invention, the section being taken on line X—Y of Fig. 2. Fig. 2 is a sectional plan through the chambers of the furnace shown in Fig. 1. Fig. 3 is a transverse sectional elevation of the furnace shown in Figs. 1 and 2, the section being taken through the central chamber. Fig. 4 is a detail of the door for the furnace shown in Figs. 1, 2 and 3.

In a convenient embodiment of this invention such as illustrated by the drawings, the process is conveniently carried on in three chambers,—a central chamber A with which the fire box communicates or in which the liquid or gaseous fuel is combusted, and 105 110

two other chambers B, C, one on each side of the said central chamber. With this arrangement the whole of the furnace gases may be directed to either or both of the said side chambers B, C, after they have traversed the central chamber A, and when the whole of the gases are directed to the one side chamber, preliminary heating may be carried on in the other side chamber by radiation through the side wall. In the case of billets and such like articles to be heated the final heating may be carried on in the central chamber, the latter constituting a secondary combustion chamber which the furnace gases enter after leaving the solid fuel fire box, but for all general processes of reheating the temperature of the side chamber is sufficiently high to complete the operation.

20 The central chamber A may communicate with the side chambers B, C, by way of flues d' open adjacent one end of the chamber A, which pass underneath the floor h of the side chambers and communicate with such chambers by regulable apertures d'' which are arranged at intervals throughout the length of the chamber on one or both sides thereof. It is to be noted by particular reference to Figs. 1 and 2 of the drawing, that 25 apertures d' are enlarged at the floor h of chamber B and C providing ledges g upon which may rest a stone block or other form of dampers g' , having a recess g'' in the upper face thereof. This provides a convenient and efficient means whereby the apertures d'' may be controlled, the dampers g being moved to open or close communication with either chamber B or C, by the aid of an iron rod, having a hooked end, to be inserted 30 into the apertures g'' of the dampers to facilitate moving the same. Any other practical form of damper, rendering either of the chambers B or C inaccessible to the flow of gases, may be provided without departing from the spirit or scope of my invention.

35 The central chamber is deeper than the side chamber to accommodate the fused metal and slag which are tapped off in the usual manner.

40 In the application of gaseous fuel fittings to a furnace of this description, the gas is admitted by way of a series of ducts e at the one extremity a' of the central chamber A, opposite from the openings of flues d' thereto and the necessary quantity of air is introduced by flues f in the side walls intermediate chamber A and chambers B and C, which flues open into the central chamber by apertures or perforations f' arranged at intervals throughout the length of the chamber.

45 The doors T may conveniently be composed of fireclay sections t held in a suitable frame t' as shown in Fig. 4.

50 The gases which enter either or both of the chambers B and C may find egress

through flues b which communicate with suitable stacks, not shown in the drawings, and by manipulation of dampers g' the full heat of the fire box may be conveyed to encounter the ore in either chamber, or both 70 chambers as previously stated.

The operation of the device is as follows:—Assuming that the dampers of apertures d'' are positioned to close said apertures in chamber C, the main or primary heating chamber A is heated in any suitable manner, either by solid fuel or by gas, and inasmuch as the dampers controlling secondary chamber B are open, the waste gas from the main or primary chamber is conveyed through such secondary chamber, and furthermore, heat that may radiate through the walls from the main or primary chamber to the secondary chamber C. If the contents of chamber A are being subjected 85 to a finishing heat, then the waste gas may be used in secondary chamber B to partially heat the material before it is subjected to the finishing heat in chamber A. Meanwhile materials can be placed in chamber C, such material being acted upon by the heat radiated through the wall between the chambers A and C, and receives the initial heat. When the finished material in chamber A has been removed, the material in chamber 90 B is placed in chamber A and the waste gas from the latter conveyed through chamber C, by opening dampers d' controlling the apertures d'' in chamber C and closing the similar apertures in the chamber B. The 95 chamber B may then receive the material to be initially heated by radiation through the wall between chambers B and A. The treatment of materials may thus continue by reversing or alternately directing the flow 100 of gases through the secondary chambers.

I claim:

1. A metallurgical furnace comprising in combination, means forming a primary chamber and secondary chambers at each side thereof, with a heat radiating wall between the primary chamber and each secondary chamber, said walls being provided with a longitudinal flue having ports leading into said primary chamber, both said primary and secondary chambers being adapted to receive the material to be treated, and having openings for communication with said secondary chambers adjacent the other end, and means for rendering either 110 of said secondary chambers inaccessible to the flow of gases from said primary chamber, substantially as and for the purpose set forth.
2. A metallurgical furnace comprising in 115 combination, means forming a primary chamber and secondary chambers at each side thereof, with a heat radiating wall between the primary chamber and secondary chambers, said walls being provided with a 120
3. A metallurgical furnace comprising in 125 combination, means forming a primary chamber and secondary chambers at each side thereof, with a heat radiating wall between the primary chamber and secondary chambers, said walls being provided with a 130

longitudinal flue having ports leading into said primary chamber, said longitudinal flues having their bottoms substantially level with the bottoms of the secondary chambers, both said primary and secondary chambers being adapted to receive the material to be treated, said primary chamber having means for admitting gases thereinto adjacent one end and having flues for communication with said secondary chambers, open to said primary chamber, adjacent the end opposite from the said end adjacent to which the gases are admitted, and extending under the floors of said secondary chambers and open thereinto, and dampers for controlling said flues in said secondary chambers, substantially as and for the purpose set forth.

3. A metallurgical furnace comprising in combination, means forming a primary chamber and secondary chambers at each side thereof with a heat radiating wall between the primary chamber and each secondary chamber, said walls being provided 25 with a longitudinal flue having ports leading into said primary chamber, the ports in one longitudinal flue being disposed opposite the ports in the remaining longitudinal flue, said primary and secondary chambers being adapted to receive the material 30 to be treated, and said primary chamber having means for admitting gases thereinto adjacent one end and having flues for communication with said secondary chambers, 35 open to said primary chamber adjacent the end opposite from the said end adjacent which the gases are admitted and extending under the floors of said secondary chambers and open thereinto, and means for 40 rendering either of said secondary chambers inaccessible to the flow of gases from said primary chamber, substantially as and for the purpose set forth.

4. A metallurgical furnace comprising in combination, means forming a primary 45 chamber and a secondary chamber at each side thereof, the wall between said primary chamber and each of said secondary chambers being of a heat radiating character, all of said primary and secondary chambers being adapted to receive material to be heated, 50 said primary chambers having means for admitting fuel thereinto, and passages connecting said primary chamber with each of said secondary chambers, the outlets from 55 said passages into said secondary chambers being distributed between the vertical walls thereof, and individually operable dampers for controlling said outlets.

5. A metallurgical furnace comprising in 60 combination, means forming a primary chamber and secondary chambers, one of said secondary chambers being at each side of said primary chamber and a heat radiating wall being placed between each two of 65 said chambers, both said primary and secondary chambers being adapted to receive material to be treated, said primary chamber being provided with means whereby fuel may be introduced therein, the walls of 70 said furnace being provided with passages connecting said primary chamber with each of said secondary chambers, the outlets from said passages into each of said secondary chambers being distributed over the floor 75 thereof, and said passages running underneath the floors of said secondary chambers, and individually operable dampers for controlling the outlets.

In witness whereof I have hereunto set 80 my hand in the presence of two witnesses.

L. A. SMALLWOOD.
